CHECK PAD HOLDER

Harry R. Mortensen, Moorhead, Iowa

Application February 5, 1937, Serial No. 124,271

9 Claims. (Cl. 281—1)

My invention relates to a holder for holding check pads.

An object of my invention is to provide means for holding a check pad so that the same will not become wasted due to loss, or so that the checks on the pad will be used without being destroyed or otherwise wasted.

A further object of my invention is to provide a means for securely retaining a check pad in a suitable device, which can be conveniently attached to any wall or counter, or the like, and which results in the fixing of a certain location for such checks so that they will not be misused for other purposes, or as stated above, wasted in the customary manner.

A further object of my invention is to provide holding means so that as checks are torn off, the check itself will not be unduly torn or otherwise mutilated.

A further object of my invention is to provide such holding means, which requires no adjustment and automatically holds succeeding checks as they are torn off for use.

A further object of my invention is to provide the above mentioned objects in a simple structure which can be manufactured at a reasonable cost.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a plan view showing the unit with a check pad mounted in the same,

Figure 2 is a sectional view taken along the lines 2—2 of Figure 1,

Figure 3 is an end view of the unit looking at the spring containing side,

Figure 4 is an enlarged detail of the end flange,

Figure 5 is an enlarged detail of a portion of Figure 2, and

Figure 6 is an end view looking toward the flange shown in Figure 4.

The check pads usually furnished in banks and in other establishments are usually wasted, since the checks are torn off and used for scratch paper or the pads themselves become misplaced or lost. This results annually in a great deal of waste which could otherwise be saved through suitable means for holding and retaining such pads.

I have used the character 10 to designate the rear of my device, which is made of suitable thin metal and which metal is bent upwardly at 11 thence horizontally at 12 and thence downwardly at 13, the vertical portion 11 providing a guide for the rear of the check pad 14. The portion 13 further extends into the formation 15, which is of limited width as shown in Figures 1 and 3, and

to which is securely welded or otherwise attached the leaf spring 16. The spring 16 extends angularly upward from the portion 15, and to the end thereof is attached the small extended member 17, which can be secured by spot welding. The member 17 terminates in the downwardly projecting point 18, which is adapted to compress and hold the pad at the point 19, or directly adjacent the edge of the pad or the glued portion such as 20.

The point 18 passes vertically within the open slot 21, which is of sufficient width to receive the same through the arcuate motion thereof. It will be noted that the point 18 is located centrally of the device. A further cut away portion is provided in the rear flange 13, which cut away portion is indicated by the character 22, and tapers to a greater width downwardly. The end of the base 10 terminates in a bent-over flange 23, which is bent back upon itself leaving a fairly substantial space at 24. The spring 16 normally lies in practically horizontal position and when the check pad 14 is inserted, it is held in the upper position by means of a finger of the hand retaining it by passing the finger within the opening 22.

The pad is inserted by causing the cardboard back 25 of the same to slide under the bent over flange 23 and within the space 24 (see Fig. 4), while the pad is being then guided across the face 30 10, the upper flange 11 acting as a further horizontal guide maintaining an even position of the pad. As soon as the pad reaches the central position of the device, the point 18 is allowed to come to rest, as shown in the various figures, special 35 reference being had to Figure 5. The edges of the checks then overlie the ends of the bent over flange 23, and are then free to be torn from the pad. The device can be mounted by means of suitable openings, such as 26, which are counter- 40 sunk to receive suitable flat head machine screws, or the device can be attached to a wall or counter in any other suitable manner. When the checks are torn from the pad, it will be noted particularly, that since the point 18 is directly adjacent 45 the edge, there will only be an extremely small portion of the check torn away at this point, which is so small as to be negligible and yet it will be observed that the point efficiently holds the upper 50 portion of the checks.

It should be specifically understood in connection with my device, that a loose leaf pad without the glued backing can be used in the same analogous manner. As the checks are torn from the pad, the point, due to the tension of the spring 18 will gradually travel downwardly until the last check is reached, and the tension will be efficiently applied at all times.

The flange 12 can be imprinted with advertis- 60

ing or other display means, advertising the bank providing these devices, etc.

It will now be seen that I have provided means for preventing waste of checks and the like, and 5 that I have provided means for conveniently holding and allowing the release of such checks without the necessity of extra manipulation.

It will also be seen that I have provided all 10 of the foregoing characteristics, as stated, in a construction which is simple in structure and which can be manufactured at a reasonable cost.

Some changes may be made in the construction and arrangement of the parts of my invention without departing from the real spirit and 15 purpose of my invention, and it is my intention to cover by my claims any modified forms of structure or use of mechanical equivalents, which may be reasonably included within their scope.

20 I claim as my invention:

1. A check pad holder comprising a base, an upper flange extending substantially perpendicular from said base, a lower bent-over flange being formed on the lower edge of said holder 25 and having a space therebetween, said lower flange adapted to receive the lower edge of the backboard of a pad, said upper flange adapted to maintain the upper edge of the pad in fixed position, a spring-urged point adapted to retain 30 the upper edge of the pad.

2. A check pad holder comprising a base, an upper flange extending substantially perpendicular from said base, a lower bent-over flange being formed on the lower edge of said holder 35 and having a space therebetween, said lower flange adapted to receive the lower edge of the backboard of a pad, said upper flange adapted to maintain the upper edge of the pad in fixed position, a spring-urged point adapted to retain 40 the upper edge of the pad, and including a leaf spring attached to the point and to one side of the holder.

3. A check pad holder comprising a base, an upper flange extending substantially perpendicular 45 from said base, a lower bent-over flange being formed on the lower edge of said holder and having a space therebetween, said lower flange adapted to receive the lower edge of the backboard of a pad, said upper flange adapted 50 to maintain the upper edge of the pad in fixed position, a spring-urged point adapted to retain the upper edge of the pad, and including a leaf spring attached to the point and to one side of the holder, said upper flange having an 55 opening receiving said point.

4. A check pad holder comprising a base, an upper flange extending substantially perpendicular from said base, a lower bent-over flange being formed on the lower edge of said holder 60 and having a space therebetween, said lower flange adapted to receive the lower edge of the backboard of a pad, said upper flange adapted to maintain the upper edge of the pad in fixed position, a spring-urged point adapted to retain 65 the upper edge of the pad, and including a leaf spring attached to the point and to one side of the holder, said upper flange having an opening receiving said point, said upper flange extending into a flat portion substantially parallel 70 to the base, and thence downwardly into a further portion at right angles to the base, said further portion having an opening for receiving a finger of the hand when manipulating the spring to cause said point to contact an upper pad blank.

5. A check pad holder comprising a base, an upper flange extending substantially perpendicular from said base, a lower bent-over flange being formed on the lower edge of said holder and having a space therebetween, said lower flange adapted to receive the lower edge of the backboard of a pad, said upper flange adapted to maintain the upper edge of the pad in fixed position, a spring-urged point adapted to retain 10 the upper edge of the pad, and including a leaf spring attached to the point and to one side of the holder, said upper flange having an opening receiving said point, said upper flange extending into a flat portion substantially parallel to the base, and thence downwardly into a further portion at right angles to the base, said further portion having an opening for receiving a finger of the hand when manipulating the spring to cause said point to contact an upper 15 pad blank, said point being located centrally of said base to support and retain the pad at the mid-point thereof.

6. A check pad holder comprising a base, an upper flange extending substantially perpendicular from said base, a lower bent-over flange being formed on the lower edge of said holder and having a space therebetween, said lower flange adapted to receive the lower edge of the backboard of a pad, said upper flange adapted to maintain the upper edge of the pad in fixed position, a spring-urged point adapted to retain 20 the upper edge of the pad, and including a leaf spring attached to the point and to one side of the holder, said upper flange having an opening receiving said point, said upper flange extending into a flat portion substantially parallel to the base, and thence downwardly into a further portion at right angles to the base, said further portion having an opening for receiving a finger of the hand when manipulating the spring to cause said point to contact an upper pad blank, said point being located centrally of said base to support and retain the pad at the mid-point 25 thereof, and said point being positioned to contact the pad directly and closely adjacent the upper edge thereof.

7. A check pad holder comprising a base, an upper flange extending substantially perpendicular from said base, means for retaining the lower edge of a check pad attached to the base, an upper centrally located point including a spring attached thereto and to the holder adapted to compress a point on the pad closely adjacent 30 the upper edge thereof, said point being resiliently urged downwardly to retain successive checks as they are torn from the pad.

8. A check pad holder comprising a base, a lower bent over flange being formed on the lower 35 edge of said base and having a space therebetween, said lower flange adapted to receive the lower edge of the backboard of a pad, resilient means attached centrally to said holder and to the upper portion of said base, said resilient means being spring urged at a single point against said pad.

9. A check pad holder comprising a base, means for retaining a check pad thereon, a 40 spring urged point attached centrally to the upper edge of said base adapted to retain the upper edge of the pad substantially at the center thereof.
